PERMUTATION LOCK

Sükrü Fenari, New York, N. Y., assignor of
fifty per cent to Vahdi Sabit

Application September 25, 1947, Serial No. 776,118

8 Claims. (Cl. 70—312)

1

This invention relates to locks of the combination or permutation type and has for its object the provision of a comparatively simple locking mechanism having parts easily constructed by die casting or the like to thereby reduce the cost of manufacture of a mechanism suitable for incorporation in a large variety of locking mechanisms.

Another object is to provide a lock of the character described in which the combination can be changed without taking the lock apart and without tools.

Further objects and advantages will be apparent from the following specification taken together with the accompanying drawings wherein, by way of illustration, preferred embodiments of the invention are illustrated and described. It will be understood however, that these descriptions are merely illustrative and are not limitative of the invention, which is as defined by the appended claims.

In the accompanying drawings:

Figure 1 is a side view of a lock embodying the invention;

Figure 2 is a longitudinal sectional view of the lock, Figure 1, with the operating parts in locked position;

Figure 3 is a transverse sectional view on the line 3—3, Figure 2;

Figure 4 is a view similar to Figure 2 with the operating parts in unlocked position;

Figure 5 is a transverse sectional view on the line 5—5, Figure 4;

Figure 6 is a side view of an alternate form of lock embodying the invention; and

Figure 7 is a front view of the lock, Figure 6.

Referring to Figure 2, the numeral 10 denotes one end of the lock casing to which the shackle 11 is swingably secured at 12 so that the shackle can be revolved or swing into and out of engagement with the locking pin or bolt 13 which enters an aperture 14 in the free end of the shackle. When pin 13 is extended as shown in Figure 2, the shackle is locked to the casing; when pin 13 is retracted as shown in Figure 4, the shackle is free to turn and the lock is open.

Members 15, 16 are secured by screws or rivets 17 to the end member 10 and form a fixed support for one or more pairs of concentric members, each pair of which comprises a ring 18 having a plurality of pockets 0 to 9 inclusive in its inner circumferential face. These rings may also have a peripheral flange 19 extending outwardly from its outer circumferential face.

The second member of each pair is a sleeve

2

or bushing 20 which fits within ring 18 which is supported thereon. Sleeve 20 is rotatably supported by members 15, 16.

Each sleeve has an aperture 21 extending from the bore to the outer face thereof and a pin 22 is freely slidable in said aperture. The length of pin 22 is such that normally, where the parts are in locked position as shown in Figure 3, the pin rotatably locks the ring 18 and sleeve 20 together. When the parts are in the position shown in Figure 5, the pins 22 may fall by gravity so that they no longer engage the rings 18 but lie below the outer periphery of the sleeves 20.

A locking bar 23 extends across the lock and is slidably supported between the members 15, 16. This bar has its ends notched or otherwise shaped to engage the arms 24, 25 of the means for moving bar 23. This means may comprise the upright members 26, 27 which are riveted or otherwise secured to the member 28 which extends below the lock as shown.

The upper end of member 26 either forms the locking pin 13 or is operatively connected thereto in any suitable manner.

Springs 29, 29 surround the members 26, 27 and bear against the member 28 tending to force same outwardly for a purpose to be presently described.

The lock is assembled by sliding the member 27 carrying spring 29 thereon into the recess provided therefor in the end of member 10 and then securing the members 15, 16 to 10 by the screws or rivets 17. The bar 23 is placed between members 15 and 16 before securing these members in place. The pins 22 are placed in sleeves 20 and the sleeves are assembled in the rings 18. Each pair of rings and sleeves is slipped over the members 15, 16, but a spacer 30 having a lower forked end 31 is placed between each ring as shown.

The end 32 of the casing carrying bolt 13 and member 26 is now placed against the exposed end of the mechanism assembly just described and is secured thereto by the pins or screws 17. One of the springs 29, as shown in Figure 2, surrounds the member 26 similarly to the spring 29 on the member 27. These springs are compressed when the bar member 28 is pressed upwardly, said member being secured to the uprights 26, 27. Thus, all the working parts are enclosed, the outer appearance of the lock being as shown in Figure 1.

It will be observed that the rings 18 have on their outer faces suitable indicia such as the num-

ber 0 to 9 which relate to pockets 0 to 9 within the ring, as best seen in Figure 3.

To set the combination, assuming the number 0, 0, 0, 0, 0 is chosen (or any other number), the rings 18 are rotated until all the 0's line up with the setting marks 33 on the casing. This will bring the interior slots 34 in the sleeves 20 in line with the locking bar 23. A slight pull outwardly on the member 28 will now—via the uprights 26, 27—pull the locking bar 23 downwards into the position shown in Figure 5, where said member is lightly held by springs 29, 29 and lies in the forks 31 of the spacers 30.

This operation withdraws the locking pin or bolt 13 from the socket 14 in the shackle 11 and permits the latter to be swung about its pivot 12 and the lock is open.

To lock, the shackle is swung inwardly, the member 28 is pressed inwardly and the rings 18 are moved haphazardly off the 0, 0, 0, 0, 0 combination. As the member 28 is pressed inwardly, the bolt 13 engages the socket 14 and shackle 11 is locked to the casing, the rings 18 and associated mechanism being in the locked position shown in Figure 3.

To change the combination, the lock is unlocked as previously described and while the shackle 11 is open and the mechanism is in the position shown in Figure 5, the rings 18 are revolved to set up the desired new combination, say 1, 2, 3, 4, 5. The shackle is closed by pressing the member 28 inwardly, thereby locking the lock as previously described, and thereafter the lock can only be opened by the 1, 2, 3, 4, 5 combination. Thus the combination can be changed to any combination of figures obtainable by five digits and without opening the lock casing or changing the mechanism in any way.

While a padlock has been shown and described in connection with the preceding figures, it will be obvious that the mechanism disclosed can be employed in any desired type of mechanism wherein a pin or bolt such as 13 is employed to lock the lock per se.

As an example of such a modification, reference is made to Figures 6 and 7 wherein the mechanism shown in Figures 1 to 5 is shown as incorporated into a knob lock. Here the rings 18 and their associated mechanism is mounted in the door knob 35 which is revolvably mounted on the door 39 in the usual manner. The combination mechanism is generally denoted by the numeral 36. The member 37 corresponds to the member 28 of Figures 1 to 5 and operates in the same manner. The bolt members 13, 13a are controlled the same as described in connection with the single bolt member 13, Figures 1 to 5 and engage a plate 38 secured to the door 39. In the locked position shown in Figure 6 the knob 35 cannot be turned to operate the usual latch or lock spindle 40, but upon the withdrawal of bolts 13, 13a from plate 38, the knob 35 may be operated in the usual manner.

Obviously a bolt 13 or two bolts 13, 13a can be combined with a wide variety of locking mechanisms to control same; the invention herein disclosed is not therefore limited to any particular form of lock such as the padlock and knob lock described, but may be applied to any form of locking device wherein a combination or permutation lock-controlling mechanism is desired.

What is claimed is:

1. In a lock, a flat ring having a plurality of radially disposed pockets extending inwardly from the inner face thereof, a sleeve within said

ring, said sleeve having a radial aperture extending between the inner and outer surfaces thereof, a pin in said aperture the outer end of which is adapted when in one position to lie within one of the aforesaid pockets of the ring and thereby lock the sleeve to said ring associated therewith, a fixed support extending through said sleeve and upon which said sleeve may revolve, a locking bar extending through said sleeve and movable in a plane perpendicular to the axis thereof and engaging the inner end of said pin therein, means connected to said bar for moving same in said plane to permit said pin to fall out of said pocket in said ring and a locking bolt connected to and movable with said bar.

2. The lock as claimed in claim 1 wherein there are a plurality of said rings and sleeves and wherein said fixed support includes end members laterally adjacent said rings and sleeves and said locking bar is slidably supported in said end members and said bolt extends freely from one of said members.

3. The lock as claimed in claim 1 wherein said fixed support includes end members laterally adjacent said rings and sleeves, spacers having forked lower ends, said spacers being located between said rings and embracing said fixed support and wherein said means includes a member slidably engaging said forked ends of said spacers and extending across the outer faces of said rings.

4. In a lock, a plurality of pairs of concentric members, the first member of each pair comprising a ring having pockets in its inner circumferential face and a peripheral flange extending outwardly from its outer circumferential face, the second member of each pair comprising a sleeve having a movable pin therein, the outer end of said pin normally lying within one of said pockets in said ring, whereby the ring and sleeve are revolvably secured together, a casing for said lock including a fixed support upon which said pair of members are revolvably mounted, a locking bar extending through all said members and movably mounted on said support, said bar normally engaging the inner ends of said pin to hold same in ring-engaging position, and manually operable means mounted on said casing and operatively connected to said locking bar to move the latter away from said pins in a plane perpendicular to the axes of said pins to permit said pins to fall out of the pockets in said rings and thereby release said rings from said sleeves so that same are independently movable.

5. The lock as claimed in claim 4 wherein said sleeves have pockets extending outwardly from the bores thereof and said locking bar may be moved into and out of said pockets when same is aligned therewith.

6. In a lock, a sleeve, a ring mounted upon said sleeve and revolvable thereabout, locking means including a pin extending between said sleeve and said ring and adapted to lock same together whereby the sleeve may be revolved by revolving the ring, a support for said sleeve, a member extending into said sleeve and adapted to contact said pin to move same longitudinally to cause same to engage said sleeve and ring, a locking bolt operatively connected to said member, and manually operable means connected to said member and adapted when moved in one direction to cause said member to contact said locking means while moving said bolt to locking position and when moved in another direction to disable said

locking means and move said bolt to unlocked position.

7. The lock as claimed in claim 6 wherein a spring is associated with said manually operable means and tends to move same in a direction to move said bolt to unlocked position.

8. A lock having a plurality of axially aligned sleeves, each of said sleeves having a radially disposed opening extending from the bore to the periphery thereof, a plurality of rings each having a plurality of open pockets formed in its inner face, one of said rings being revolvably mounted on each of said sleeves, a plurality of pins one in each of said radially disposed openings in said sleeves and normally lying within said openings, a member extending through the bores of said sleeves and adapted to be moved perpendicular to the axes of said bores to engage said pins and move each pin outwardly to enter a pocket in the ring on the respective sleeve when a pocket

is in alignment with each pin, and manually operable means located outside the projected diameter of said rings in engagement with said member for moving the same.
